UNITED STATES PATENT OFFICE.

ARTHUR H. JOHNSON, OF WOBURN, MASSACHUSETTS.

DESIGN FOR A BOTTLE.

Application filed April 10, 1925. Serial No. 13,082. Term of patent 14 years.

To all whom it may concern:

Be it known that I, ARTHUR H. JOHNSON, a citizen of the United States, residing at Woburn, in the county of Middlesex and State of Massachusetts, have invented a new, original, and ornamental Design for Bottles, reference being had to the accompanying drawing, forming part thereof.

The figure is an elevation of a bottle showing my new design.

I claim:

The ornamental design for a bottle, as shown.

ARTHUR H. JOHNSON.
